(57) **CLAIM**

The ornamental design for a valve and tube assembly, as shown and described.

DESCRIPTION

FIG. 1 is a perspective view of a valve and tube assembly according to the invention;

FIG. 2 is a side elevational view of the valve and tube assembly of FIG. 1;

FIG. 3 is another side elevational view of the valve and tube assembly of FIG. 2 rotated 90 degrees;

FIG. 4 is the opposite side elevational view of the valve and tube assembly of FIG. 3;

FIG. 5 is a top plan view of the valve and tube assembly of FIG. 1;

FIG. 6 is a bottom plan view of the valve and tube assembly of FIG. 1;

FIG. 7 is a perspective view of another embodiment of the valve and tube assembly;

FIG. 8 is a side elevational view of the valve and tube assembly of FIG. 7;

FIG. 9 is a side elevational view of the valve and tube assembly of FIG. 8 rotated 90 degrees;

FIG. 10 is an opposite side elevational view of the valve and tube assembly of FIG. 9;

FIG. 11 is a top plan view of the valve and tube assembly of FIG. 7; and,

FIG. 12 is a bottom plan view of the valve and tube assembly of FIG. 7.

The broken lines in the figures show boundaries of the respective embodiments of the valve and tube assembly of the present invention and form no part of the design to be patented. The areas within the broken lines are not part of the claimed invention.
